UNITED STATES PATENT OFFICE

SAMUEL KAUFFMAN, OF ST. LOUIS, MISSOURI

RADIATOR INCLOSURE

Application filed September 22, 1926. Serial No. 137,153.

This invention pertains to inclosures for radiators.

In many modern buildings, including dwellings, clubs, offices and other buildings, a great deal of attention is paid in the design and arrangement of furnishings and fittings to the artistic appearance of the interior as a whole. Great care is exercised to have all things in harmony from an artistic point of view. It is considered by many, however, that radiators of the ordinary design used for steam or hot water heating are not designed for artistic appearance and often inject a note of discord into an otherwise harmonious interior. As radiators are necessary and cannot well be dispensed with, it is desirable to provide means for covering or hiding each radiator. Such means should, moreover, be capable itself of presenting an artistic appearance in harmony with the other furnishings of the room.

One of the objects of this invention, therefore, is to provide a radiator inclosure which will screen the radiator from view without unduly impairing its efficiency as a heating unit, and which can be designed to present an appearance in harmony with an interior of any ordinary arrangement and design.

It is also desirable in most cases to provide a shield between the radiator and the wall which shall deflect the warm air current from the wall so as to prevent forming the deposit of soot and dirt upon the wall and hangings above the radiator.

Another object of this invention, therefore, is to provide such a radiator inclosure which will not only screen the radiator from view and present an attractive appearance itself, but which will prevent warm air currents from rising along the wall and causing deposits of soot and dirt thereon.

Another object of this invention is to provide such a radiator inclosure which shall be simple and economical to manufacture and durable in service.

Further objects will appear from the following description taken in connection with the accompanying drawings in which:

Figure 1 is a perspective view of a radiator inclosure embodying this invention;

Figure 2 is a horizontal section of the inclosure;

Figure 3 is a vertical section of the inclosure;

Figures 4, 5 and 6 are detail sectional views showing means for mounting the top;

Figure 7 is a detail illustrating the method of attaching the corner supports;

Figure 8 is a detail showing the mounting of the panel molding, and

Figure 9 is a detail showing the top mounted directly on the frame.

Referring to the drawings 1 designates an open skeleton frame which may be constructed of sheet metal or other suitable material reinforced if necessary by angle iron or other suitable reinforcing elements 2. The frame 1 is constructed so as to surround or embrace the radiator at its front and sides. The openings in the frame are bridged by panels 3 which may be also of sheet metal or other suitable material and which may further be perforated in a decorative pattern of any suitable kind so as to render the device as a whole attractive in appearance. If desired the panels may be bordered by molding 4 mounted on the frame by means of fasteners 5 bearing on cross members 20 insertable through slots 21 in the back of the molding, as shown in Figure 8. Additional corner braces 17 may be applied to the frame 1 where necessary. This frame may be constructed as shown in Figure 5, with angle reinforcements 2, or as shown in Figure 9 where the frame itself is constructed of angle iron. In either case the panels 3 are usually welded to the frame.

The back 6 of the inclosure may be mounted in a manner similar to the mounting of the panels 3, but said back is imperforate so as to prevent warm air passing therethrough from the radiator to the wall.

The corners of the frame 1 are covered by corner members 7 which may be constructed of wood, metal or other suitable material and which are preferably of convex form recessed to receive the corner of the frame as illustrated in Figure 7. The corner members 7 may be attached to the frame by means of screws 8 passing through the frame and if de-

sired through the panels 3. These members 7 may be provided with feet 9 and serve as supports for the radiator inclosure. The members 7 may be formed with such outline 5 or otherwise decorated so as to harmonize with the decorative scheme of the inclosure as a whole.

The inclosure is provided with an imperforate top 10 which may be of metal or 10 similar material and which may be provided with a downturned flange 11 adapted to fit loosely over the frame 1 and provided on the inside with one or more spring retainers 12 adapted to make frictional engagement with 15 the frame 1 to retain the top in place. In the embodiment shown in Figure 5 the top is constructed from a slab of marble, glass or other similar material 13 which is held in place on the frame by a pin 14 frictionally engaging 20 a suitable recess in the slab. In the embodiment of Figure 6, the top 10 is formed with an upstanding marginal rim 15 within which the slab 13 may be laid to rest upon the top 10.

In all these cases the top is imperforate and 25 joins with the imperforate back 6 to provide a shield or deflector which will deflect the rising currents of warm air away from the wall to force the same to pass out of the inclosure through the front or side panels. The air is 30 thus directed into the room instead of along the walls. Those parts of the frame 1 which extend along the back and top at the sides or ends of the radiator assist in directing the air to prevent the warm air from rising 35 from the inclosure close to the wall. The deposit of soot and dirt upon the wall is, therefore, prevented by this construction.

A door 16 may be provided in one or both 40 sides of the inclosure to permit access to the radiator for operating the valves thereof or other purpose. This door may be arranged to open outwardly and be provided with a spring 22 for automatically closing the same. This construction provides for proper operation 45 of the radiator without detracting from the appearance of the inclosure.

It will be seen that this invention provides a radiator inclosure of simple construction and which lends itself readily to artistic design 50 signs of various forms. The open skeleton frame lends itself to a variety of designs and the panels in the openings of the frame may be perforated so as to carry out any desired decorative motif, while the corner members 55 7 may be formed and decorated to harmonize with the whole. The inclosure as a whole forms an oblong housing which itself is adapted to fit harmoniously into almost any scheme of interior design. Furthermore, 60 while this inclosure is capable of almost any desired decorative effect its utility is in no way impaired in order to obtain such result. The imperforate back and top together with the marginal portions of the frame 1 adjacent 65 thereto form an effective deflector for guiding

the upwardly moving air currents away from the wall and into the room. The construction, furthermore, is simple and its manufacture may be carried out economically as sheet metal is a material which is simple to handle in any manufacturing processes. 70

It is obvious that various changes may be made in the details of construction without departing from the spirit of this invention; it is to be understood, therefore, that this invention is not to be limited to the specific details shown and described. 75

Having thus described the invention what is claimed is:

1. A radiator inclosure, comprising, an open skeleton frame having front, rear and side members and upright corner supports, said members connecting said supports to form a self-contained supporting structure, a perforated decorative panel mounted on 80 said frame so as to bridge the opening therein, and separate decorative corner members mounted on and supported by said supports and adapted to cover the same. 85

2. A radiator inclosure, comprising, an open skeleton frame having front, rear and side members and upright corner supports, said members connecting said supports to form a self-contained supporting structure, a perforated decorative panel mounted on 90 said frame so as to bridge the opening therein, and separate decorative corner members of outstanding convex form mounted on and supported by said supports and adapted to 95 cover the same. 100

3. A radiator inclosure, comprising, an open skeleton frame having front, rear and side members and upright corner supports, said members connecting said supports to form a self-contained supporting structure, a perforated decorative panel mounted on 105 said frame so as to bridge the opening therein, an imperforate back adapted to fit behind the radiator, an imperforate top adjacent thereto and cooperating therewith to deflect air currents, and separate decorative corner members mounted on and supported by said supports and adapted to cover the same. 110

4. A radiator inclosure, comprising, an open skeleton frame having front, rear and side members and upright corner supports, said members connecting said supports to form a self-contained supporting structure, a perforated decorative panel mounted on 115 said frame so as to bridge the opening therein, an imperforate back adapted to fit behind the radiator, an imperforate top adjacent thereto and cooperating therewith to deflect air currents, and separate decorative corner members of outstanding convex form mounted on 120 and supported by said supports and adapted to cover the same. 125

5. A radiator inclosure, comprising, an open skeleton frame having front, rear and 130

side members and upright corner supports, said members connecting said supports to form a self-contained supporting structure, a perforated decorative panel mounted on 5 said frame so as to bridge the opening therein, an imperforate back adapted to fit behind the radiator, an imperforate top adjacent thereto and cooperating therewith to deflect air currents, and separate decorative 10 corner members of outstanding convex form mounted on and supported by said supports and adapted to cover the same, said corner members being recessed to receive said supports.

15 6. A radiator inclosure, comprising a series of structural metal upright and horizontal members connected to form a self-contained skeleton frame, decorative panels mounted in said frame, and decorative corner posts attached to the corners of said 20 frame.

7. A radiator inclosure, comprising a series of structural metal upright and horizontal members connected to form a self-contained skeleton frame, decorative panels 25 mounted in said frame, decorative corner posts attached to the corners of said frame, and a top mounted on said frame.

8. A radiator inclosure, comprising a series of structural metal upright and horizontal members connected to form a self-contained skeleton frame, an air deflecting back mounted in said frame, decorative panels mounted in said frame, and decorative corner posts attached to the corners of 30 said frame.

In testimony whereof I affix my signature
this 4th day of December, 1925.

SAMUEL KAUFFMAN.
